US00D960528S

(12) **United States Design Patent** (10) **Patent No.:** **US D960,528 S**
(45) **Date of Patent:** ** *Aug. 16, 2022

(54) **HOODED GARMENT**

(71) Applicant: **Shun On John Ngan**, Carson, CA (US)

(72) Inventor: **Shun On John Ngan**, Carson, CA (US)

(*) Notice: This patent is subject to a terminal disclaimer.

(**) Term: **15 Years**

(21) Appl. No.: **29/773,235**

(22) Filed: **Mar. 8, 2021**

Related U.S. Application Data

(63) Continuation of application No. 29/704,843, filed on Sep. 6, 2019, now Pat. No. Des. 912,370.

(51) **LOC (13) Cl.** **02-02**

(52) **U.S. Cl.**

USPC **D2/831**

(58) **Field of Classification Search**

USPC D2/823, 825, 826, 828, 831

CPC A41D 1/00; A41D 3/08

See application file for complete search history.

(57) **CLAIM**

The ornamental design for a hooded garment, as shown and described.

DESCRIPTION

FIG. 1 is a perspective view of my hooded garment; FIG. 2 is a front view thereof; FIG. 3 is a right side view thereof; FIG. 4 is a left side view thereof; FIG. 5 is a back view thereof; FIG. 6 is a top view thereof; FIG. 7 is a bottom view thereof; FIG. 8 is a front view thereof with the sleeves down; and, FIG. 9 is a back view thereof with the sleeves down. The broken lines shown in the drawings depict portions of the hooded garment that form no part of the claimed design.

1 Claim, 7 Drawing Sheets
